UNITED STATES PATENT OFFICE.

HARRY S. LYTLE, OF NORTH BROOKFIELD, ASSIGNOR TO ALFRED H. BATCHELLER, OF BOSTON, MASSACHUSETTS.

EYELETING-MACHINE.

SPECIFICATION forming part of Letters Patent No. 397,597, dated February 12, 1889.

Application filed November 20, 1888. Serial No. 291,374. (No model.)

To all whom it may concern:

- Be it known that I, HARRY S. LYTLE, of North Brookfield, county of Worcester, and State of Massachusetts, have invented an Improvement in Eyeletting-Machines, of which the following description, in connection with the accompanying drawings, is a specification, like letters on the drawings representing like parts.
- 10 This invention has for its object to provide an eyeletting-machine of the kind shown and described in United States Patent No. 272,382, granted to L. D. Hawkins February 13, 1883, with a delivery or conveying attachment for the eyelet-pieces removed from the material by the eyelet-punch. The eyeletting-machine referred to has an automatic feed besides other automatic devices, and in practice the eyelet-pieces, flying promiscuously, clog the machine 15 so much as to greatly impair the feed as well as other parts, and to enable the machine to accomplish the ends desired for it the eyelet-pieces must be conveyed from the machine.
- 20 The invention therefore consists in the combination, with the tubular eyelet-punch and mechanism for moving it, of a delivery or conveying tube attached to the upper end of said punch to convey the eyelet-pieces away from the machine, the delivery or conveying tube 25 herein shown consisting of a tube made of spirally-wound wire, the successive convolutions of the wire lying close to each other.

Figure 1 shows in side elevation an eyeletting-machine of the kind referred to, provided 30 with a delivery-tube for the eyelet-pieces in accordance with this invention; and Fig. 2, a vertical section of the tubular eyelet-punch and a portion of the delivery-tube sufficient to show the point of attachment of the tube 35 to the punch.

The tubular punch *c*, its operating-lever *c'*, pivoted at *c²* to an arm, *c³*, which is attached

to a head, *d*, extending sufficiently forward to provide a bed for the punch *c*, the grooved cam *f*, mounted upon the driving-shaft *b*, the 45 vertical rod *f'*, having its bearings in the main frame-work *a* of the machine and connected at its upper end to the arm *c'*, are all as shown in the patent referred to, wherein similar letters of reference indicate like parts. 50

To the upper end of the tubular punch *c* a delivery or conveying tube, *i*, is attached, to deliver or convey the eyelet-pieces punched from the material away from the machine to a convenient place. The delivery-tube is 55 herein shown as made of wire wound spirally, the successive convolutions lying so close together as to form a tube. This form of tube is very efficient, as the movement given to it by the arm *c'* keeps it in motion, so that the 60 eyelet-pieces are moved freely along.

The tube *i* may be of any length desired, and may lead to a suitable box or other receptacle, (not shown,) which receives the eyelet-pieces. 65

I claim—

In an eyeletting-machine, the tubular eyelet-punch and mechanism for moving it, combined with a delivery or conveying tube of spirally-wound wire attached to and forming 70 a continuation of the tubular eyelet-punch, for delivering or conveying from the machine the eyelet-pieces punched from the material, the vibration of the tube moving said eyelet-pieces freely therethrough, substantially as 75 described.

In testimony whereof I have signed my name to this specification in the presence of two subscribing witnesses.

HARRY S. LYTLE.
